CUSHION HEEL

Carl Z. Litschert, Cleveland Heights, Ohio

Application May 21, 1938, Serial No. 209,300

3 Claims. (Cl. 36—35)

My invention relates to lifts and heels for shoes and in particular to that type of heel which permits maximum resiliency to extreme edge of heel.

5 One object is to provide a means whereby a rubber heel may be superimposed over a lift without the use of nails.

Another object is to provide a cushion tread by providing air spaces between the lift and the heel entirely around the heel adjacent the outer edge thereof where resiliency is most needed as is shown by the obvious wear at this point.

10 Another object is to provide a lift and heel of simple construction and easy application which will have a longer life and tend to increase comfort in walking.

15 These and other objects and advantages may be noted from the following specification and its accompanying illustration in which:

20 Fig. 1 is a top plan view of the heel.

Fig. 2 is a bottom plan view of the lift.

Fig. 3 is a section through the assembled heel and lift.

Fig. 4 is a perspective view of the assembled heel and lift with the lift partly broken away.

25 Fig. 5 is a modified form of Fig. 3 showing a slightly different heel.

Fig. 6 is a section showing a modified form for partial replacement tread where heels are nailed on.

30 Fig. 7 is a section showing a full sized tread without the air space, also for replacement.

Again referring to the illustration, a lift 10 has a groove 11 on the lower face adjacent the edge of said lift and entirely therearound is shown in Fig. 2.

35 A heel 12 is shouldered adjacent the edge at 13 said shoulder forming a projecting rib 14 therearound. A wedge shaped flange 15, undercut at 15a and 15b, through the middle of the top surface of the heel 12 has a V-shaped groove 16 along the middle thereof. The rib 14 is undercut at 14a and 14b on one side and at 14c on the opposite side, as shown in Fig. 3 specifically, for greater resiliency, said undercuts tapering out as shown by dotted lines in Fig. 1.

40 When the heel 12 is cemented to the lift 10, the cement 17 is placed in the groove 11 of the lift 10 and on the rib 14 of the heel 12, the rib 14 being inserted in said groove 11 there is thus formed an air space 18 between the lift 10 and the heel 12, around the entire inner edge of the rib 14.

45 As no nails are used in the construction or assembling of this heel and lift the resultant wear is greatly diminished and the resiliency is actually increased.

50 In the modified form illustrated in Fig. 5 the lift 10 with its groove 11 is the same as that here-

5 inabove described, but the heel 20 is slightly different in construction, the rib 21 is undercut at 21a and 21b outside and at 21c inside with a tapering ridge 21d inside. The double flanged center portion 22 is undercut at 22a and 22b along the outer edges thereof and has a recess 23 through its middle.

Fig. 6 illustrates a replacement heel 25 having a projecting rib 26 which is cemented within a groove 27 in a lift 28 nailed to the lift 29. No air chamber is used in this type of partial replacement.

Fig. 7 illustrates a full sized tread replacement without an air chamber, the tread or heel 30 has a projecting rib 31 inserted in a groove 32 in the lift 33 and cemented therein.

My construction provides maximum resiliency. The rib 14 being grooved on both sides, and extending completely around top edge of lower lift, results in resiliency at extreme edge of heel, 20 which is where it is mostly needed, as worn heels plainly indicate.

The supporting flange in the center is also grooved in such a manner so it will not interfere with any resiliency within the wall.

25 The rib projecting from the top of the heel, the groove in upper lift for receiving this rib and the top of the center flange or rib are used for cementing the lifts together.

As no nails are used with this construction the 30 resiliency of the heel actually increases with wear, while it decreases with wear where nails are used and where there is no air space.

The rib and groove construction can also be used for a partial replacement tread where heels 35 are nailed on as shown in Figure 5 and also for a full size tread without the air spaces as shown in Figure 7.

This rib and groove method of attaching prevents any water or moisture from coming in 40 contact with the cemented parts, in case any part of the edge should become accidentally loosened.

I claim:

1. A cushion heel comprising a lift having a 45 groove extending around the bottom surface near the outer edge thereof, and a resilient tread having a rib extending around the top surface thereof and fitting in the groove, the said top surface having air pockets between the lift and heel tread when said parts are fastened together, the said top surface of the tread also having a middle flange projecting to contact with the lift. 50

2. A cushion heel as in claim 1, the sides of the rib being undercut to increase the resiliency 55 thereof.

3. A cushion heel as in claim 1, the flange being undercut at its sides.

CARL Z. LITSCHERT.
